UNITED STATES PATENT OFFICE

2,327,130

FURNACE DOOR

Charles H. Russell, McKeesport, Pa.

Application January 23, 1941, Serial No. 375,692

2 Claims. (Cl. 110—173)

This invention relates to improvements in furnace doors of the character adapted for heating furnaces, as for example, open hearth furnaces and the like.

In prior practice, such furnace doors have generally been of solid rigid construction suspended over the furnace opening in the usual manner. Such doors have been found to be too inflexible and to warp under the heat of the furnace, causing either the ends or the center portion of the door to be disposed or pull away from the furnace. Thus, cold air gains access to the furnace, making it difficult to maintain uniform temperatures and increasing fuel consumption.

I have discovered that these difficulties may be obviated in an economical and simple manner by constructing the door so as to permit the same to expand and contract with the furnace wall.

My invention contemplates the provision of an articulated door so disposed and constructed as to insure the close conformity thereof with the furnace wall under expansion due to heat.

Additional objects and advantages of the invention will become apparent from the following description, taken in connection with the accompanying drawing, wherein:

Fig. 1 is an elevational view of a furnace door embodying my invention;

Fig. 2 is a top plan view thereof;

Fig. 3 is an end elevation thereof;

Fig. 4 is a cross-section taken on the line IV—IV of Fig. 1; and

Fig. 5 is an elevational view of a modified form of door embodying the invention.

Referring to the drawing, the improved furnace door is shown positioned over the opening of a furnace A, as for example, an open hearth furnace, said door comprising at least two vertically disposed parts 2 and 3 hinged at their meeting vertical edges, as indicated at 4—4. The parts or sections 2 and 3 are preferably formed of outer metal plates or shells 5 filled or lined with refractory 6, as shown in Fig. 4 said refractory lining being disposed toward the interior of the furnace A.

The hinged sections 2 and 3 thus provide an articulated door which may be suspended by a bridle 7 pivotally secured to the upper edges 8 of the sections in any suitable manner, as by ears 9. The points of attachment of the bridle 7 or ears 9 are preferably secured to the door sections substantially in the vertical planes of their respective centers of gravity, whereby the

hinged assembly is in substantial balance when suspended vertically over the furnace opening. The bottom edge of the door may engage the foreplate 10 of the furnace when the door is in closed position.

The hinged connections 4—4 preferably have sufficient play therein to permit the center portions of the door sections 2 and 3 to move inwardly and outwardly in response to a corresponding movement of the furnace wall. Such furnaces generally bow or belly horizontally outward at their door sections when heated, and the articulated door of my invention may deflect therewith without destroying the closing function thereof. It will be observed that any tendency to produce such outward displacement of the center of the door will result in a conforming pressure of the door upon the furnace wall, thus maintaining a proper closure, said pressure resulting from the corresponding outward displacement of the lower ends of the bridle 7, the upper end of said bridle (not shown) being maintained over a pulley or the like, as is customary.

Where spaced hinges 4—4 are employed as in Fig. 1, I prefer to seal the vertical meeting edges of the door sections 2 and 3 between said hinges by a cover plate or stop 11, said plate being carried by one door section and overlying the face of the other door section.

Fig. 5 illustrates a modified form wherein the door sections 2 and 3 are joined by a single vertical hinge 4 extending substantially throughout the vertical height of the center portion of the assembled door.

It will be apparent that a furnace door of the character described will possess sufficient flexibility, due to its plurality of self-adjusting sections, to readily and simply conform to the furnace wall and maintain a suitable closure in service. By reducing the dimensions of the door sections or parts, the tendency thereof to warp is likewise minimized, thus providing a highly economical and efficient door. Such a door will have a long life of service.

Various changes and modifications are contemplated within the scope of the following claims.

I claim:

1. An articulated door adapted to be freely and vertically suspended over a vertical furnace opening or the like, said door including a pair of vertical sections having their adjacent vertical edges hinged to permit relative movement of said sections in a horizontal direction, means for suspending said sections in substantial balance in

cluding a hanger attachment disposed in the vertical plane of the center of gravity of each section, common suspending means connecting said attachments, whereby said door may conform to the face of the furnace wall about the opening in accordance with the deformation of said wall face due to heat, and means at the hinge connection of said sections covering the joint between the sections during relative movement thereof.

2. An articulated door adapted to be freely and vertically suspended over a vertical furnace opening or the like, said door including a pair of vertical sections, spaced hinges connecting the sec-

tions at their adjacent vertical edges, a bridle having attachment with the upper edge of each section substantially in the vertical plane of its center of gravity for freely suspending the door, 5 whereby said door may conform to the face of the furnace wall about the opening in accordance with the deformation of said wall face due to heat, and a cover plate secured to one section and overlying the other section at their adjacent 10 vertical edges, said plate extending between the hinges, whereby the joint between the sections is covered during relative movement thereof upon said hinges.

CHARLES H. RUSSELL.
